(57) **CLAIM**

The ornamental design for top for step ladder, as shown and described.

DESCRIPTION

FIG. 1 is a perspective view of the top for step ladder according to the present invention.

FIG. 2 is a front view of the top for step ladder according to the present invention.

FIG. 3 is a left side view of the top for step ladder according to the present invention.

FIG. 4 is a right side view of the top for step ladder according to the present invention.

FIG. 5 is a rear view of the top for step ladder according to the present invention.

FIG. 6 is a top view of the top for step ladder according to the present invention; and,

FIG. 7 is a bottom view of the top for step ladder according to the present invention.

The broken lines in all views are for illustrative purposes only and form no part of the claimed design.

1 Claim, 3 Drawing Sheets
